UNITED STATES PATENT OFFICE.

ADOLF PILGER, OF MARSHWOOD, PENNSYLVANIA.

DEVICE FOR INDICATING THE PROXIMITY OF ICEBERGS.

1,247,325.

Specification of Letters Patent. Patented Nov. 20, 1917.

Application filed March 16, 1917. Serial No. 155,306.

To all whom it may concern:

Be it known that I, ADOLF PILGER, a subject of the Emperor of Germany, resident of Marshwood, county of Lackawanna, and 5 State of Pennsylvania, have invented certain new and useful Improvements in Devices for Indicating the Proximity of Icebergs, of which the following is a specification.

This invention relates to improvements in 10 safety devices for ships, and has as its principal object the provision of means whereby the imminent proximity of icebergs or ice-flows may be determined and an audible signal giving warning of the fact.

15 Other objects are the provision of such means in forms which may be readily applied or installed in boats of any character whatever, either in their original construction or added thereafter.

20 These and other like objects are attained by the novel construction and combination of parts hereafter described and shown in the accompanying drawings, forming a material part of this disclosure, and in which:—

25 Figure 1 is a vertical diagrammatic view taken through the waist of a large sea-going vessel, indicating the application of the invention.

Fig. 2 is an enlarged side elevation showing the principal details of construction, and

Fig. 3 is a vertical sectional view taken on line 3—3 of Fig. 2.

Fig. 1 represents a conventional view illustrative of the general arrangements on the larger sea-going ships, the numeral 10 indicating substantially the water line or depth of submergence, the hold 11 therebelow, containing the boilers, engines, and other machinery which is partially protected by coal bunkers 12, while the horizontal lines 14 indicate the various decks.

One of the smoke stacks 15 has adjacent to it a steam pipe 16, provided at its top with 45 a whistle 17, in this case used as a danger signal, operated through the rod 18.

Depending below or at least level with the lowermost part of the hull of the vessel is a tube 20 having an inlet 21 provided with a 50 strainer or the like to prevent the entrance of seaweed, fish, etc., into the pipe leading to a pump 22, here shown to be of the cen-

trifugal type and which is used to force the water into a tank 23; an outlet 24 is provided to permit a constant circulation 55 throughout the tank, which is thus kept constantly filled with water of the temperature through which the vessel is sailing.

Formed with the cover 26, of the tank 23, is a well or central depression 27 containing 60 a cylinder 28, open at its top 29 and filled partially with a substance 30, as mercury, the bulk of which is expansible or contractible by changes in temperature.

Floating on the top of the mercury is a 65 plunger 31 to which is attached a rod 32 leading to a lever 33 which has engaged with it the signal operating rod 18. Thus if the vessel approach a zone of extremely cold water, the same is immediately transmitted 70 into the tank 23, chilling the mercury, causing it to contract or shrink so as to lower the plunger 31, automatically operating a signal, announcing audibly that the vessel is within a danger zone, so that precautions may be taken to escape therefrom.

Ordinarily, the apparatus is arranged so that normally no signal is given as none is required. It will be noted that the operation of the apparatus is entirely automatic 80 and controlled by the temperature of the surrounding water.

Having thus described my invention, what I claim as new, and desire to secure by Letters Patent, is:—

1. In a ship having an audible signal, the combination with a tank, and means for circulating the water in which the vessel floats through said tank, of a cylinder partially submerged in said tank, said cylinder having a closed lower end, a plunger operable in said cylinder, means combined with said plunger for operating the mentioned signal, and means in said cylinder for actuating said plunger upon a change of temperature 95 of the water circulating through said tank.

2. In a ship, the combination with a tank and a pump for supplying water thereto from below the ship, of means providing a circulation of water through said tank, a second tank supported in the first named tank, a float movable in said second tank, means in said second tank adapted to contract or expand according to the tempera- 100

ture of the water in the first named tank, and means operated by said float for producing an audible signal.

3. In a ship, the combination with a water tank having inlet and outlet pipes and an audible signal means, of a pump in said inlet pipe by which water from below the vessel is caused to circulate through said

tank, a mercury holding cylinder engaged in said tank, a float supported by the contents thereof, and means combined with said float for operating said signal.

In testimony whereof I have affixed my signature this 16th day of February, 1917.

ADOLF PILGER.
